UNITED STATES PATENT OFFICE.

EDWARD M. STILES, OF MOUNT PLEASANT, IOWA, ASSIGNOR TO U. S. SLICING MACHINE COMPANY, OF CHICAGO, ILLINOIS, A CORPORATION OF ILLINOIS.

ATTACHMENT FOR MEAT-SLICING MACHINES.

1,192,014.

Specification of Letters Patent. Patented July 25, 1916.

Application filed October 18, 1912. Serial No. 726,459.

To all whom it may concern:

Be it known that I, EDWARD M. STILES, a citizen of the United States, residing at Mount Pleasant, in the county of Henry and State of Iowa, have invented certain new and useful Improvements in Attachments for Meat-Slicing Machines, of which the following is a specification.

This invention relates to improvements 10 in attachments for slicing machines, particularly adapted, though not necessarily limited in its use, to meat slicing machines of the type in which the meat is supported upon a table and fed to a cutter, the cutter and table being relatively movable to effect 15 the cutting operation.

One of the objects of the invention is to provide an improved attachment of this 20 class having means for automatically collecting and stacking the slices as they are cut, and thereby obviate the necessity of gathering the slices by hand and stacking them.

A further object is to provide an improved device of this class which will be 25 simple, durable, cheap and compact in construction, and effective and efficient in operation.

To the attainment of these ends and the 30 accomplishment of other new and useful objects as will appear, the invention consists in the features of novelty in substantially the construction, combination and arrangement of the several parts hereinafter 35 more fully described and claimed and shown in the accompanying drawings, exemplifying the invention and in which—

Figure 1 is a top plan view of an improved device of this class, constructed in 40 accordance with the principles of this invention, showing the same applied to a slicing machine. Fig. 2 is a side elevation of the parts shown in Fig. 1, and with the parts in the position they will assume when they 45 are receiving the slice from the cutter and when the slice is about to be dumped from the receiver to the collector. Fig. 3 is a detail front elevation of the slice engaging face of the receiver and the fly, and as taken 50 on line 3—3, Fig. 2. Fig. 4 is a detail sectional view as taken on line 4—4, Fig. 2. Fig. 5 is a view similar to Fig. 2, of another form of the invention. Fig. 6 is a detail sec-

tional view taken on line 6—6, Fig. 5. Fig. 7 is a detail view of the tripping cam shown 55 in Fig. 5. Fig. 8 is a detail view in elevation as taken on line 8—8, Fig. 5. Fig. 9 is a top plan view of one of the receiving surfaces shown in Fig. 5.

Referring more particularly to the drawings, and in the present exemplification of this invention, the numeral 10 designates a rotary cutter and 11 a meat supporting table for holding the meat to be sliced, which table is adapted to be reciprocated so as to 60 effect a cutting operation, while the meat is advanced laterally upon the table, with respect to the cutter in the ordinary and well known manner.

Arranged adjacent to the cutter 10 is a 70 horizontally disposed receiver designated generally by the reference numeral 12, having receiving surfaces 13, which, in the present exemplification of this invention are curved or semicircular, arranged adjacent 75 each end of the receiver and are inclined upwardly from the receiver and in directions from the extremities of the receiver toward the axis of rotation of the receiver. The receiver with these faces 13, is rotatable 80 about an upright axis designated generally by the reference numeral 14 journaled in a suitable bearing and rotary motion is imparted thereto in any suitable manner, preferably by means of a gear 15 connected with 85 the axle, and with which the second gear 16 meshes. This gear 16 is connected with a shaft 17, journaled in a suitable bearing and a gear 18 is also connected with the shaft, which latter gear meshes with the gear 90 19 on the shaft 20, the latter receiving motion from any suitable source.

The surfaces 13 of the receiver may be spaced from each other any suitable distance and arranged adjacent the path of rotation 95 of the receiver is a support, designated generally by the reference numeral 21 upon which is arranged an inclined collector support 22, the latter being preferably curved and provided with a series of teeth 23. The 100 receiver has a circular path of movement and a constant direction of rotation, while the adjacent edge of the support 21 is concaved to permit the edge of the receiver and curved receiving surfaces 13 to move 105 in close proximity thereto. Arranged also

adjacent the path of movement of the surfaces 13 and fixed against bodily movement with relation to the collector support 22 is a fly designated by the reference numeral 24. 5 This fly is provided with spaced fingers 25 and the fingers are offset with respect to the body portion of the fly as at 26, shown more clearly in Figs. 1 and 2 for a purpose to be set forth. This fly is pivotally supported 10 by means of a horizontal axis 27, preferably in the form of an axle, and is pivoted to the support 21, and an elastic member 28, preferably in the form of a spring coiled about the axle 27 is provided which tends normally 15 to move the fly in a direction away from the collector support 22. The faces 13 are constructed so as to form spaced slice engaging portions 29 as shown more clearly in Figs. 2 and 3, each of which portions is provided 20 with teeth 30 adapted to penetrate the slice as it is cut and thereby receive it from the cutter and hold it in position until it is delivered to the collector support 22 by the fly 24. The fingers 25 of the fly are also curved 25 as shown in Fig. 1 to conform to the contour of the surfaces 13 and are so spaced from each other that as the receiving surface advances toward the fly after having received the slice, the fingers will pass into the spaces 30 between the slice engaging portions 29 of the receiving surface to pass beneath the slice. The off set portion 26 of the fly permits the fingers 25 to enter the spaces between the portions 29 of the receiver to 35 pass beneath the slice and prevents the fingers from striking the ends of the portions 29.

The fly may be tripped against the tension of the elastic member 28 in any desired 40 or suitable manner, and for this purpose there may be provided an arm 31 which is connected with the fly and which projects therefrom in a direction toward the axis of rotation of the receiver. Carried with the receiver are cams 32, one of which is provided 45 for each of the surfaces 13 and are so arranged that the arm 31 of the fly projects into the path of movement of the cams when they are rotated by the movement of the receiver. The cams are so arranged that just 50 about the time the receiving surface registers with the fly and the collector support 22, one of them will engage the arm 31 of the fly to rock the latter against the tension of the elastic member and thereby cause the fingers 55 of the fly to lift the slice from the receiving surface and deliver it to the collector support 22 and against the slice previously deposited. The cam face which engages the arm 31 may be of any desired length so that 60 it will act on the arm to hold the fly in the tripped position if desired, or it may be a short cam which passes immediately out of engagement with the arm as soon as the fly 65 is tripped and the slice delivered. Ob-

viously, the cams may be adjustably secured to the receiver so that they may be properly positioned, or so that the time of their engagement with the fly arm may be varied.

In order to accommodate for the increasing size of the stack of slices that are delivered to the collector support, the latter is preferably adjustably mounted with respect to the support 21. This may be accomplished by means of the tongue and groove 70 connection 33-34, see Fig. 4, and the connection is such that there may be sufficient friction between the collector support 22 and the support 21 to hold the former in position to receive the slice and then permit it 75 to be moved with respect to the support 21 a distance substantially equal to the thickness of the slice being delivered thereto, by the fly. A guard 35 may also be provided adjacent the cutter 10 which co-operates 80 with the receiving surface to direct the slice 85 to the surface.

In the forms of the invention shown in Figs. 5 to 9, the receiving surfaces 36 depend from the bottom of the receiver 12 90 and these surfaces are provided with slots or openings 37 to form the spaced slice engaging portions 38, the latter being provided with teeth 39 similar to the teeth 30. The slots 37 extend in a direction lengthwise of the axis of rotation of the receiver and are of a width somewhat greater than the width of the fingers 40 of a fly designated generally by the reference numeral 41, see Fig. 8. The fly 41 is pivoted on a 95 horizontal axis 42 and is fixed with respect to the support 21, being preferably pivoted thereto. In this form of the invention, the elastic member which is coiled about the axle 42 in a manner similar to that shown in Fig. 1, tends to hold the fly normally in a position that the receiving surfaces 36, as they approach the collector support, will pass over the fingers 40 of the fly. When the receiving surface assumes a 100 position adjacent the collector support 22, the spaces 37 of the receiving surface will be adjacent the fingers of the fly and at which time the fly is tripped so that the fingers will pass from under the surface 110 and slice through the respective openings 37 to engage the slice, lift it from the receiving surface and deliver it to the collector support 22. Any suitable means may be provided for thus operating the fly. A 115 simple and efficient means for accomplishing this result comprises a cam designated generally by the reference numeral 43 in Fig. 5, secured to the axle 44 of the receiver. This cam is provided with two high portions 45 having intermediate low portions 46. An arm 47 is pivoted intermediate its end as at 48 to a fixed support and is arranged so that one extremity 49 will be in a position to be acted upon by the 120 125 130

high portions 45 of the cam. The other extremity of the arm is connected in any suitable manner as by means of a link 50 with an arm 51 on the fly. Thus it will be seen that when the receiver 12 is rotated, the cam 43 will be correspondingly rotated and the high portions 45 of the cam are so arranged that when one of the receiving surfaces 36 assumes the proper position with respect to the fingers of the fly, and the collector support 22, one of the high portions of the cam will act on the arm 47 to trip the fly, and the low portions are of such a length that the fly will be held in the proper position to permit the receiving surface to pass the fly. When the cams pass out of engagement with the arm 47, the elastic member will return the fly and likewise the arm 47 to their proper positions. Obviously, any number of the receiving surfaces 36 may be provided and when more than two are provided, it is also obvious that a properly shaped cam should also be provided.

25 While there has been described and shown the preferred forms of the invention and the manner the desired results may be accomplished, it is to be understood that various changes may be made within the 30 scope of the claims in the construction and arrangement of the various parts, without departing from the spirit of the invention.

What is claimed as new is:—

1. The combination of a meat slicer, a 35 receiver movable adjacent the slicer for receiving the slices therefrom and traveling in a circular path, means for imparting motion to the receiver, a collector support, and means connected with the support and 40 with respect to which last recited means the receiver is movable, for supporting and transferring the slices from the receiver to the collector support.

2. The combination of a meat slicer, a 45 receiver movable adjacent the slicer for receiving the slices therefrom and traveling in a circular path, said receiver having a constant direction of rotation, means for imparting motion to the receiver, a collector support, means connected with the support and with respect to which last recited means the receiver is movable, for transferring the slices from the receiver to the collector support, and means for intermittently actuating the said transferring means.

3. The combination of a meat slicer, a receiver movable adjacent the slicer for receiving the slices therefrom and traveling 60 in a circular path, means for imparting motion to the receiver, a collector support, means connected with the support and with respect to which last recited means the receiver is movable whereby the slice will be carried by the receiver into a position to be

engaged by the last said means, and means controlled by the movement of the receiver for actuating the last recited means to transfer the slices from the receiver to the collector support.

4. The combination of a meat slicer, a receiver movable adjacent the slicer for receiving the slices therefrom and traveling in a circular path, means for imparting such movement to the receiver, a collector support, and an intermittently actuated fly operating to support and lift the slices from the receiver and deliver them to the collector support, said fly being separate from the receiver and connected with the collector support, and being adapted to assume such a position with respect to the slice engaging surface of the receiver that the movement of the receiver will position the slice to be engaged by the fly.

5. The combination of a meat slicer, a receiver movable adjacent the slicer for receiving the slices therefrom as they are cut, said receiver traveling in a circular path, means for imparting such movement to the receiver, a collector support for the slices, and means separate from the receiver and movable across the path of movement of the slice engaging surface of the receiver for taking the slices from the receiver and delivering them to the collector support.

6. The combination of a meat slicer, a receiver movable adjacent the slicer for receiving the slices therefrom as they are cut, said receiver traveling in a circular path, a collector support, and a fly operating between the receiver and the collector support, said fly being independent of the receiver and arranged adjacent the path of movement of the slice engaging surface of the receiver and movable in one direction across the said path to assume a position to one side of the approaching slice, and in another direction to lift and transfer the slice from the receiver to the collector support.

7. The combination of a meat slicer, a receiver movable adjacent the slicer for receiving the slices therefrom as they are cut, said receiver traveling in a circular path, a collector support, a fly operating between the receiver and the collector support, said fly being independent of the receiver and arranged adjacent the path of movement of the slice engaging surface of the receiver and movable in one direction across the said path to assume a position to one side of the approaching slice, and in another direction to lift and transfer the slice from the receiver to the collector support, and means whereby the movement of the receiver will intermittently actuate the fly.

8. The combination of a meat slicer, a receiver rotatable in a circular path and having an upright surface movable adjacent the slicer for receiving the slices as they are cut,

a collector support, and means for transferring the slices from the said surface to the collector support, the said means embodying a fly connected with the support and with 5 relation to which fly the said receiver is rotatable, and tripping means for the fly operating with the receiver.

9. The combination of a meat slicer, a receiver traveling in a circular path and 10 shaped to form spaced slice engaging portions, a collector support for the slices, and a fly independent of the receiver for transferring the slices from the receiver to the collector support, said fly connected with the 15 support and operating transversely of the path of movement of the said portions and having spaced members movable into and out of the spaces between the slice engaging portions of the said receiver.

20 10. The combination of a meat slicer, a receiver traveling in a circular path and shaped to form spaced slice engaging portions, a collector support for the slices, a fly independent of the receiver for transferring the slices from the receiver to the collector support, said fly connected with the support and operating transversely of the path of movement of the said portions and having spaced members movable into and 25 out of the spaces between the slice engaging portions of the said receiver, and means whereby the movement of the said receiver will thus actuate the fly.

11. The combination of a meat slicer, a receiver movable in a circular path adjacent the slicer and about an upright axis, said receiver having an upright slice engaging surface, a support adjacent the path of movement of the receiver, and a fly with respect to which the said surface is rotatable, said fly connected with the support and operating between the support and receiver and movable across the path of movement given to the slices by the receiver, to transfer the slice from the receiver to the support, said fly being adapted to assume a position between the slice engaging surface and the axis of rotation of the said surface.

12. The combination of a meat slicer, a receiver movable in a circular path adjacent the slicer and about an upright axis, said receiver having an upright slice engaging surface, a support adjacent the path of movement of the receiver, a fly with respect 50 to which the said surface is rotatable, said fly connected with the support and operating between the support and receiver and movable across the path of movement given to the slices by the receiver, to transfer the slice from the receiver to the support, said fly being adapted to assume a position between the slice engaging surface and the axis of rotation of the said surface, and means controlled by the movement of the 55 said surface for tripping the fly.

13. The combination of a meat slicer, a receiver movable in a circular path adjacent the slicer and about an upright axis, said receiver having an upright slice engaging surface, a support adjacent the path of 70 movement of the receiver, and a fly fixed adjacent said path of movement of the receiver and with respect to which fly the said surface is rotatable, said fly operating between the support and receiver and movable across the path of movement given to the slices by the receiver, to transfer the slice from the receiver to the support, said fly being adapted to assume a position between the slice engaging surface and the axis of rotation of the said surface, the said fly being provided with spaced portions and the said surface being provided with spaces into and out of which the said portions of the fly are movable.

85 14. The combination of a meat slicer, a receiver movable adjacent the slicer and in a circular path about an upright axis for receiving the slices as they are cut, a support, a fly independent of the receiver and with respect to which the receiver is rotatable, said fly being movable across the path of movement given to the slices by the receiver, for delivering the slices to the support from the receiver, and means for causing the fly to be moved into a position that it will pass under the approaching slices and while the slices are still carried by the receiver.

95 15. The combination of a meat slicer, a receiver movable adjacent the slicer and in a circular path about an upright axis for receiving the slices as they are cut, a support, a fly independent of the receiver and with respect to which the receiver is rotatable, said fly being movable across the path of movement given to the slices by the receiver, for delivering the slices to the support from the receiver, means for causing the fly to be moved into a position that it will pass under the approaching slices and while the slices are still carried by the receiver, and means for tripping the fly to lift the slices from the receiver and stack them upon the support.

110 16. The combination of a meat slicer, a traveling receiver adjacent the cutter for receiving the slices therefrom, a fly coöperating with the receiver, and a support to which the slices are delivered by the fly as they are taken from the receiver, the said fly being connected to the support and with respect to which fly the receiver is bodily movable.

115 17. The combination of a slicer, a receiver movable adjacent the slicer for receiving the slices therefrom, means for imparting motion to the receiver, a collector support, and means connected with the support and with respect to which last recited means the 125 130

receiver is movable, for supporting and transferring the slices from the receiver to the collector support.

18. The combination of a slicer, a receiver 5 movable adjacent the slicer for receiving the slices therefrom, means for imparting motion to the receiver, a collector support, means independent of the receiver and connected with the support and with relation 10 to which means the receiver is movable, the said means being responsive in its movement to the movement of the receiver and operating to transfer the slices from the receiver to the support.

15 19. The combination of a slicer, a receiver 50 movable adjacent the slicer for receiving the slices therefrom, means for imparting motion to the receiver, a collector support, means independent of the receiver and connected with the support and with relation 20 to which means the receiver is movable, the said means being responsive in its movement to the movement of the receiver and operating 25 to pass beneath the slice as it is advanced by the receiver to lift the slice from the receiver to the support.

20 20. The combination of a slicer, a receiver 55 movable adjacent the slicer for receiving the slices therefrom, means for imparting motion 30 to the receiver, a collector support, and means supported independent of the receiver and connected with the support for transferring the slices from the receiver to the support, the last recited means being 35 movable into and out of active position with respect to the receiver and being responsive in its movement to the action of the receiver.

25 21. The combination of a slicer, a receiver 60 movable adjacent the slicer for receiving the slices therefrom, means for imparting motion to the receiver, a collector support, and means connected with the support and with respect to which last recited means the receiver is movable, for supporting and transferring 45 the slices from the receiver to the collector support, the said receiver having a constant direction of movement.

22. The combination of a slicer, a receiver 65 movable adjacent the slicer for receiving the slices therefrom, means for imparting motion to the receiver, a collector support, and means connected with the support and with respect to which last recited means the receiver is movable, for transferring the slices from the receiver to the collector support, the last recited means being movable back and forth across the path of movement of the receiver.

60 23. The combination of a slicer, a receiver 70 movable adjacent the slicer for receiving the slices therefrom, means for imparting motion to the receiver, a collector support, and means connected with the support and with respect to which last recited means the re-

ceiver is movable, for transferring the slices from the receiver to the collector support, the said receiver being movable toward and away from the second recited means.

24. The combination of a slicer, a receiver 75 movable adjacent the slicer for receiving the slices therefrom, means for imparting motion to the receiver, a collector support, and means connected with the support and with respect to which last recited means the receiver is movable, for transferring the slices 80 from the receiver to the collector support, the said receiver having a constant direction of movement and being movable toward and away from the second recited means.

25. The combination of a slicer, a receiver 85 movable adjacent the slicer for receiving the slices therefrom, means for imparting motion to the receiver, a collector support, and means connected with the support and with respect to which last recited means the receiver is bodily movable, the said means 90 operating to support and transfer the slice from the receiver to the support.

26. The combination of a slicer, a receiver 95 movable adjacent the slicer for receiving the slices therefrom, means for imparting motion to the receiver, a collector support, and means connected with the support and with respect to which last recited means the receiver is bodily movable, the said means 100 operating to transfer the slice from the receiver to the support and being responsive in its movement to the movement of the receiver.

27. The combination of a slicer, a receiver 105 movable adjacent the slicer for receiving the slices therefrom, means for imparting motion to the receiver, a collector support, and a fly connected with the support and with respect to which fly the receiver is bodily 110 movable, the said fly operating to transfer the slice from the receiver to the support.

28. The combination of a slicer, a receiver 115 movable adjacent the slicer for receiving the slices therefrom, means for imparting motion to the receiver, a collector support, and a fly connected with the support and with relation to which fly the receiver is bodily 120 movable, said fly operating to transfer the slices from the receiver to the support, and being responsive in its movement to the bodily movement of the receiver.

29. The combination of a slicer, a receiver 125 movable adjacent the slicer for receiving the slices therefrom, means for imparting motion to the receiver, a collector support, and a fly connected with the support and with relation to which fly the receiver is bodily movable, said fly operating back and forth across the path of movement of the receiver to transfer the slices from the receiver to the support, and being responsive in its movement to the bodily movement of the receiver.

30. The combination of a slicer, a receiver movable adjacent the slicer for receiving the slices therefrom, means for imparting motion to the receiver, a collector support, a fly connected with the support and with relation to which fly the receiver is movable toward and away from, said fly being movable back and forth across the path of movement of the receiver for transferring the slices 5 therefrom to the support, means for moving the fly in one direction and means for moving the fly in another direction.
31. The combination of a slicer, a receiver movable adjacent the slicer for receiving the slices therefrom, means for imparting motion to the receiver, a collector support, a fly connected with the support and with relation to which fly the receiver is movable toward and away from, said fly being movable 10 back and forth across the path of movement of the receiver for transferring the slices therefrom to the support, means for moving the fly in one direction and means for moving the fly in another direction, one of the 15 last two recited means being operatively connected with the receiver.
32. The combination of a slicer, a receiver movable adjacent the slicer for receiving the slices therefrom, means for imparting motion to the receiver, a collector support, a fly connected with the support and with relation to which fly the receiver is movable toward and away from, said fly being movable 20 back and forth across the path of movement of the receiver for transferring the slices therefrom to the support, means for moving the fly in one direction and means for moving the fly in another direction, one of the 25 last two recited means being operatively connected with the receiver.
33. The combination of a meat slicer, a receiver movable adjacent the slicer, for receiving the slices therefrom, means for imparting motion to the receiver, a collector support and a fly pivotally mounted upon 30 the support and with respect to which fly the 35
- 40
- 45

receiver is bodily movable, the said fly operating to transfer the slice from the receiver to the support.

34. The combination of a slicer, a receiver 50 movable adjacent thereto, a collector support, and means mounted upon the collector support for supporting and transferring the slices from the receiver to the collector support.

35. The combination of a slicer, a receiver movable adjacent thereto, a collector support, and means mounted upon the collector support for supporting and transferring the slices from the receiver to the collector support, the said means being responsive in its movement to the movement of the receiver.

36. The combination of a slicer, a receiver movable adjacent thereto, a collector support, and a fly mounted upon the collector support for supporting and transferring the slices from the receiver to the collector support.

37. The combination of a slicer, a receiver movable adjacent thereto, a collector support, and a fly mounted upon the collector support for supporting and transferring the slices from the receiver to the collector support, the said fly being responsive in its movement to the movement of the receiver.

38. The combination of a slicer, a collector support, a traveling receiver disposed between the two for receiving the slices from the slicer and means fixed with relation to the collector support for transferring the slices from the receiver to the collector support, said receiver also traveling with respect to the said means.

In testimony whereof I have signed my name to this specification, in the presence of 85 two subscribing witnesses, on this 16th day of October A. D. 1912.

EDWARD M. STILES.
